UNITED STATES PATENT OFFICE.

ANNA LEE KELLEY, OF PYRITON, ALABAMA.

DESIGN FOR A BASKET.

Application filed January 15, 1927. Serial No. 20,399. Term of patent 7 years.

To all whom it may concern:

Be it known that I, ANNA LEE KELLEY, a citizen of the United States, residing at Pyriton, in the county of Clay and State of Alabama, have invented a new, ornamental, and original Design in Baskets, of which the following is a specification, reference being had to the accompanying drawing, forming part thereof.

The figure is an elevation of a basket showing my new design, the base ornamentation being pine cones and the body being covered with pine needles, and the upper border being formed by overlying pine cone petals.

I claim:

The ornamental design for a basket as shown and described.

ANNA LEE KELLEY.
